JAR LIFTER

Buell Eckert, Fremont, Ind., assignor of one-third
to Claude H. Douglass and one-third to John
Stafford, both of Angola, Ind.

Application October 7, 1936, Serial No. 104,494

4 Claims. (Cl. 294—100)

My invention relates to improvements in jar lifters, and has for its objects to provide a lifter including a positive and secure frame, having a convenient transverse handle, and vertical strong, though formed of metal, strips upon which the desired manipulating elements are slidably mounted, and also guided for opening and closing jaws to grip the neck of the jars for which the lifter is intended, together with spring members connecting the frame with said jaws for actuation of the latter as will be explained in detail.

It is a further object of my lifter to provide vertical coil springs adjacent the inner face of the respective frame strips to make readily attachable or detachable the lower ends of the coils upon the lower ends of said strips, whereby detachment of these parts makes easily replacement of the new springs when fracture requires it. Another object is to mount the upper portions of the sliding elements pivotally together, and thereby require no other pivotal connection of parts,—a very desirable advantage, as later explained.

Other objects and advantages will be apparent from the following description and the accompanying drawing in which:—

Figure 1 is a side view showing the jaws engaging the neck of a jar;

Figure 2 is a side elevation of the lifter showing the jaws separated;

Figure 3 is a front elevation of the device;

Figure 4 is a vertical, longitudinal section of the lifter taken in a plane indicated by the line 4—4 of Fig. 3;

Figure 5 is a transverse sectional view taken in a plane indicated by 5—5 of Fig. 4;

Figure 6 is a fragmentary detail of the lower tip of one of the frame strips, and portions broken away, and

Figure 7 is a perspective view of a detachable detail fastener for the tip flange.

The lifter shown and described in this specification comprises an upper frame device 5 which is without flexibility and is quite rigid, the jaws 6 which act to engage the neck 7 of the jar, being guided by mounting the jaw members 8 upon said device 5 for relative movement thereon, and thereby movement of the jaws to and away from each other, being accomplished and controlled.

The frame 5 comprises an integral metal strip of flat material whose original form is longitudinal, having an intermediate broadened portion whose lateral edges 9 are, in manufacture, turned upwardly and toward each other, to form the strong tubular handle portion 10, as seen in Figs.

1 to 4 of the drawing. The vertical and narrower strips 11 are parallel to act as support for the body of the lifter.

The lower ends 12 of the bent down strips 11 are bent toward each other forming a flange 13 on each, which flanges are provided with convenient means for attachment thereon of one end of the spring coil 14 to be later more fully explained. Slightly above the ends 12 of the strips 11, a broadened and integral flange 15 is provided on either side of the strip 11, thereby providing four such flanges 15 on the frame 5. The outer edges of said flanges 15 are bent inwardly at 16, as shown in Figs. 3 to 6, and the inner edges 17 of the flanges 15 are shaped oblique to the length 15 of the strips, so that the intervening space between such edges 17 very positively widens in an upward direction. Such edges 17 are not in contact with the strip faces, but are open sufficiently to receive jaw members 8 into such inclined inner spaces 18 which are sufficiently open to, not only admit the members 8, but permit slight movement of the members 8 laterally in such spaces 18. Such inclined spaces 18 furnish the guides for actuating the jaws 6 in opening or closing, by the latter rising or falling by manual operation.

The actuation of the jaw members depends in my construction shown, by forming them of strong wire separately, on opposite sides of the jar to be lifted and carried. To this end either member 8 is integral and comprises a loop having parallel rods 8 slidable lengthwise of the corresponding inclined spaces 18 within the flanges 15 of the frame 5, the upper ends of the members 8 are bent toward the inner face of the adjacent strip 11, and then joined by an integral cross rod 19, while the lower ends are bent inwardly and outwardly where they are integrally joined by arcuate connections to form the gripping jaws 6; whereby raising members 8 in the guides 16 tends to open the jaws 6, and lowering them tends to force the jaws toward each other to grip the neck 7 of the jar.

The various parts which comprise the jar lifter are each completely formed in such a manner that subsequent to their assembly the formations will serve to lock the parts together without further deforming of any of the parts. To this end each flange 13 which is bent inwardly as shown in Fig. 6 is provided with a pair of arcuate recesses 23 forming between them an ear 24. After the jaw members 8 have been inserted in the guides formed by the flanges 16 a clip or shell 25 is slipped over each flange 13 and when so posi-

tioned prevent the jaws from being moved inwardly a distance sufficient to prevent their removal.

These shells 25 are then locked in position by the looped end 28 of the springs 14. As shown in Fig. 7 each shell is recessed on its upper and lower faces as indicated at 21. Such recesses overlie the slots 23 whereby the springs 14 when positioned as indicated in Fig. 4 lock the shells 10 in position on the flanges 13.

The ends of the wire which form the jaws 8 are brought together and form the cross rods 19. Thus it will be seen that prior to the insertion of the jaws in the frame 11 these ends of the wires or jaws 8 may be spread apart for insertion in the pivot sleeve 20. This sleeve is provided at either end with a downwardly turned ear 21. Each of these ears is provided with a suitable opening to receive the upper looped ends of their respective springs 14. Inasmuch as the springs 14, when in their normal position, are in tension it is obvious that the springs will serve as final locking members to retain the various parts in their assembled operating positions.

When the jaw members 8 are inserted laterally in the respective bent flange members 15, the latter, being integral with the strips 11, are positioned slightly above the flanges 13, but out of contact with the latter. The ends of the flanges 13 are apt to present a sharp edge for receiving thereon the pressure of the inner surface of the rods 8, unless friction at that point is reduced, which I attain by mounting the shells 25 telescopically on the respective flanges 13, and thereby providing curved edges 26 against which the rods 8 may move, both longitudinally in the spaces 18, and also laterally while limited thereby, as will be evident. The provision of the coils 14 with one end hook detachably connected to the ear 21, and the other hook connected to the tip 24 by means of the slots 23, will serve to urge the members 8 downwardly, and at the same time hold the shell 25 well on the flange 13, securely but detachably, and expose the tip 24 for fastening the coil 14.

The concave edges 27 permit the coil ends 28 to engage the neck of the tip 24 without slipping off such tip. Movement of the members 8 and connected parts downward in the guides 16 forces the members toward each other, and thereby closing the jaws 6 into gripping relation, as shown in Fig. 1, which I may utilize to grip the neck 7 of a jar. These members 8 are then pivoted together at 20, and operating as levers, whereby raising the parts 19 and 20 by the fingers of the hand while retaining a grip of the handle 10, opens the jaws 6 and releases the jar, which grip, of another jar, is effected by merely positioning the jaws thereon while releasing the hold on the part 20, so that the coils 14 automatically lower the members 8 and 6, and thereby close about the neck 7 of the second jar. The normal position of the jaws when not positively controlled manually, is a closed one about the jar neck. This is clearly shown in Figs. 3 and 4.

In operation, assuming that the lifter is applied to a jar or other similar receptacle having a neck about which the jaws 6 are gripped at 7, and the jaws closed automatically by the action 70 of the springs 14 tending to lower the members 8, the hand may grasp the handle 10 and thereby carry the jar to any spot desired where it may be deposited; when the same hand may reach down to the lower tube 20 enclosing the rods 19 therein, and then manually grip the two parallel members

20 and 10 together or toward each other. This movement draws the members 8 with their arcal grip jaws 6, upward through the guides 16 thereby separating the rods 8 and opening the jaws 6, so that the jar is released, and the lifter may 5 then be applied to another receptacle neck, where manual release of the device causes the jaws to grip the latter jar. In this operation, the rods 8 are held in the guides by the outer curves at 16, and the curved ends 26 prevent inward movement 10 of the rods, while the upper portions of the gripping members are permitted to separate somewhat by the pivotal action of the rods 19 in the tube 20.

Very effective action of the jaws 6 is attained 15 by application of force to both these members 8, and the jar is gripped by the springs 14 without manual force applied to any part, the handle only being grasped, unless the jaws are to be released. The coils 14 are very readily replaced, 20 if they are broken, and their ends are easily engaged with the parts 21 and 24, respectively. Such coils 14 may also be used which are stronger or weaker, as may be found advantageous. Other changes may be made in the structure 25 shown, without departing from the scope of my invention, and as limited only by the following claims.

Having described my invention, what I claim as new is:

1. A jar lifter comprising a normally erect frame member having spaced and parallel strips and lateral flange members bent to form oppositely inclined guide members, a pair of bowed gripping members slidably mounted in the respective guides, and having pivotal means for connecting the upper ends together, for swinging relative to each other, opposite inwardly directed concave jaws on the lower ends of said bowed members, and a frame flange below the plane of 40 said guides to resist unlimited inner movement of said bowed members to leave the guides.

2. A jar lifter comprising a substantially vertical frame member having spaced and parallel flat strips whose upper ends are joined by a 45 tubular handle, and each of the lower ends having lateral flange members bent oppositely upon themselves to form spaced and inclined guide members, a pair of bowed gripping members slidably mounted in the respective guides and having means for pivotally connecting the upper ends of the bowed members together one upon the other, oppositely inwardly directed concaved jaws at the lower ends of said bowed members; and spring means connecting the frame strips with 50 the pivots of the gripping members for normally closing said jaws.

3. A jar lifter comprising a metal strip frame having an intermediate handle portion, parallel strips integral with the handle, the lower end of 60 each strip being widened to form lateral cross flanges in a plane transverse of the handle, guide elements formed by bending said lateral cross flanges inwardly upon themselves but spaced from the same, and directed oblique to the strips, a 65 pair of bowed gripping members slidably mounted in the respective guides, so that upward movement of the bowed members in the guides tends to separate the bows, means for pivotally connecting the upper ends of the bows together, 70 gripping jaws at the lower ends of the bows, and means for connecting the pivotal portion of the gripping members with the lower ends of the strips to normally lower the jaws in said guides and thereby close the jaws together.

4. A jar lifter comprising a metal strip frame having an intermediate handle portion, and spaced parallel strips extending downward from the handle, the lower ends of the strips having cross flanges in a plane transverse of the handle, the ends of the cross flanges being bent upon themselves to form inclined guides, a pair of bowed members having arcuate jaws on their lower ends, so that vertical movement of the latter in the guides will tend to separate or close said jaws, a pair of coil springs for vertical mounting adjacent the inner faces of said strips and connected at their ends to the upper ends of the bowed members and the lower ends of the strips, respectively, the lower ends of the strips having inwardly bent slotted flanges for attachment of the coils thereto, and a hollow, flat shell having one lateral concave edge to receive therein the slotted flanges and thereby expose the slotted edge of the flange for connection of the coils. 5
